UNITED STATES PATENT OFFICE.

WILLIAM J. TANGERMAN, OF HAMMOND, INDIANA.

TANK-CAR ANCHORAGE.

1,261,182.

Specification of Letters Patent.

Patented Apr. 2, 1918.

Application filed March 16, 1916. Serial No. 84,559.

To all whom it may concern:

Be it known that I, WILLIAM J. TANGERMAN, a citizen of the United States, and residing at Hammond, Lake county, Indiana, have invented certain new and useful Improvements in Tank-Car Anchorages, of which the following is a specification.

My invention relates to railroad tank cars and has special reference to those which are characterized by an underframe that rests upon the trucks and is provided with cradles in which the tank is lodged.

The underframe is of greater length than the car body or tank and is relied upon to receive and transmit the stresses and shocks incident to coupling, starting and stopping.

Formerly it was thought sufficient to provide chocks on the underframe at the ends of the tank to prevent the endwise shifting of the latter, but now that it is customary frequently to heat the contents of tank cars to facilitate unloading, it is necessary to anchor the tank to the underframe by means which shall permit the tank and the underframe to expand and contract independently. The devices used for this purpose are called "anchorages". They are placed between the bottom of the tank and the underlying portion of the underframe and prevent the endwise shifting of the tank bodily on the underframe, but leave the tank free to expand and contract on said frame.

Obviously an anchorage in that position is subject to tremendous strains which tend to tear it apart from the tank and underframe. I find that by reason of defects in principle and construction all of the anchorages now in use fail properly to distribute the shocks upon their fastenings and that often they are broken or damaged to an extent which disqualifies the car for use. I find furthermore that all present forms of anchorages induce, and are subjected to vertical strains which cause the bending of the bottom of the tank and the tearing out of the rivets or bolts by which they are attached to the tank and frame.

The object of my invention is to overcome these difficulties; and, more particularly, to provide a shock distributing anchorage which shall resolve all shocks and stresses in lines parallel to the axis of the car and thus avoid vertical strains in the anchorage between the tank and frame;—to provide an anchorage which shall dis-

tribute the strains uniformly upon its fastenings;—to provide an anchorage which preferably shall permit the free lifting of the tank from the car without disturbing any of the anchorage fastenings;—and finally to provide an anchorage which shall be of more simple and economical construction and more durable and effective than any now in use. Other objects of the invention will appear hereinafter.

The principle and general nature of my invention, and also the structural details of the best embodiment thereof which I have thus far devised, will be readily understood on reference to the drawings that form part of this specification, in which:—Figure 1 is a side elevation of a tank car embodying my invention;—Fig. 2 is an enlarged transverse section on the line 2—2 of Fig. 1;—Fig. 3 is a partial side view of the anchorage, taken from Fig. 2;—and, Fig. 4 is a plan view of the anchorage, the tank being removed, as upon the curved line 4—4 of Fig. 2.

The familiar parts shown in the drawings are the car trucks, 2—2; the bolster cradles, 3—3; the underframe sill or girder, 4; the intermediate cradles, 5; the body or tank, 6; the tank straps, 7; and the tank outlet or unloader, 8.

The parts 3, 4, and 5 are the chief elements of the underframe above mentioned.

The cradles of the underframe are preferably so designed that the bottom, 6', of the tank is several inches above the top, 4', of the underframe.

My novel anchorage, A, is placed, and acts, between the top, 4', of the sill and the bottom, 6', of the tank, near one of the bolsters, 3.

The sill, 4, is usually composed of two channel beams, 4'', connected by cover plates, 4'''. As will presently be understood, it is desirable and also most convenient to apply the anchorage to the top flanges of the center sill or girder, 4. While it is feasible to position it midway on the top of the sill, 4, I prefer to make it in laterally separated sections positioned over the top flanges of the sill, 4. Further, the anchorage may occupy any desired longitudinal position on the sill, 4, but I find it most desirable and effective when placed as shown; that is, with its outer end close to one of the bolsters, 3, and with its inner end extending toward the middle of the car,

The length of the anchorage is determined by the size of the tank and the thickness of the plates and flanges to which the complementary parts of the anchorages are riveted.

5 The two sections of the anchorage, A, are parallel. Each section comprises two complementary members, *a*, and, *b*. The lower member, *a*, is preferably an angle-bar having its lower flange attached by a row of rivets, *c*, to the plate, 4", and top flange of beam 4". The vertical flange of the angle bar is notched and thus provided with a series of spaced upstanding rectangular teeth or lugs. The upper member, *b*, of 10 the anchorage, A, is a channel or trough preferably formed of sheet metal and presenting edges which are attached to the bottom of the tank, 6, by three rows of rivets. A single row, *e*, is used at the inner edge of 15 the trough and two rows of rivets, *f*, are preferably used for attaching the outer and upper edge of the trough shaped member to the tank. The sides, *b'*, of the member, *b*, preferably converge downwardly and are 20 joined by a flat bottom portion, *b''*. The bottom, *b''*, contains a row of slots, *g*, of sizes to snugly admit the corresponding teeth, *d*, of the member, *a*; which teeth extend upwardly through the slots, *g*, as best 25 shown in Fig. 2.

30 I prefer that the edges of the serrations or teeth, *d*, shall be vertical rather than inclined, but my invention contemplates the inclination thereof. My invention also contemplates the inversion of the members, *a* and *b*. The thin tank plates afford the least secured fastenings for rivets, but provide the best footing for the flanges of the trough shaped members and I therefore much prefer 35 the arrangement shown, with the fine distribution of rivets on the widely separated lines made possible by the application of the trough-shaped member to the tank.

40 The parallel sections of the anchorage mutually aid one another to prevent both longitudinal movement and rotation of the tank on the underframe.

45 When desired the tank may be lifted off the underframe without disturbing the fastenings. As the complementary members of the anchorage are engaged through the medium of vertical teeth the tank may be either removed, or lowered into position, without necessitating the disturbance of any of the 50 rivets by which the complementary members of the anchorage are secured.

55 When the car is subjected to an endwise shock, the force is communicated to the tank through the medium of, and the shifting of 60 the tank is prevented by, the intermeshing upper and lower members of the anchorage. Each tooth of the anchorage takes its part of the load and communicates it directly to that part of the complementary member 65 which it engages. In this manner the force

is distributed uniformly throughout the length of the anchorage and the latter is relieved from vertical strains which would tend to bend the ends of the complementary parts and pull out the rivets. Under these 70 conditions every rivet in the anchorage is subjected only to shearing strains and each rivet is permitted to effect its maximum resistance to the shock.

An important feature of my invention is 75 that the line of engagement thus provided between the tank and underframe is substantially midway of the height of the anchorage and that the bending arms of the anchorage are thereby shortened one-half as 80 compared with the bending arms of those anchorages in which the line of engagement is on the tank or on the sill. This shortening of the effective bending arm of the anchorage causes it to act reliably without 85 bending, and hence the danger of bending the bottom plates of the tank is avoided.

A distinct advantage of the anchorage shown lies in the fact that all of the rivets are in open, easily accessible positions, an 90 item of interest in considering the cost of the car.

The extreme simplicity, durability and economy of my novel anchorage will be apparent to car builders and users. 95

Various modifications of my invention will readily suggest themselves to one who is skilled in the art, and except as specifically pointed out in the appended claims, I do not limit the invention to the precise 100 construction herein shown and described.

Having thus described my invention, I claim as new and desire to secure by Letters Patent:—

1. A tank car tank anchorage comprising, 105 in combination, two complementary members, having oppositely faced bases and one thereof provided with a longitudinal row of teeth and the other being formed with a longitudinal row of recesses to receive said 110 teeth.

2. A tank car tank anchorage comprising a trough-shaped member containing a longitudinal row of perforations, in combination with a complementary member having teeth 115 in said perforations.

3. A tank car tank anchorage comprising a bar presenting a row of rectangular teeth, in combination with a complementary trough-shaped bar having rectangular portions interfitting with the teeth of said bar. 120

4. A tank car tank anchorage comprising a trough-shaped member containing a longitudinal row of slots, in combination with a complementary member provided with a longitudinal row of teeth each substantially 125 filling a slot in said trough-shaped member.

5. A tank car tank anchorage comprising a tank member containing a longitudinal row of slots, in combination with an underframe 130

member presenting a corresponding row of teeth in said slots.

6. A tank car tank anchorage comprising a trough-shaped member containing a longitudinal row of oblong perforations in combination with a complementary member having a row of rectangular oblong teeth respectively fitting said perforations.

7. A tank car tank anchorage comprising an angle bar having one flange provided with a row of rivet holes and having its other flange notched and thus provided with a row of oblong teeth, in combination with a trough-shaped bar provided with two flanges containing rows of rivet holes and having in its bottom a row of oblong slots complementary to the teeth of said angle bar.

8. In a tank car an underframe, in combination with a tank horizontally disposed thereon, one anchorage member applied to said underframe, a second member applied to the bottom of said tank, one of said members having a row of teeth and the other a row of perforations therefor, and said mem-

bers being intermeshed in a horizontal plane intermediate said tank and underframe.

9. A tank car tank anchorage, comprising a bar member, having an edge formed with a plurality of teeth, in combination with a parallel member formed with a plurality of slots to receive said teeth.

10. A tank car tank anchorage comprising a member having a portion secured to the car tank, and a portion spaced therefrom, said spaced portion having a plurality of recesses, in combination with a complementary member having teeth entering said recesses.

11. A tank car tank anchorage comprising a rolled metallic shape having a portion secured to the car tank, and a portion spaced therefrom, said spaced portion being formed with recesses, in combination with a rolled shape having a plurality of teeth entering the recesses in said member secured to the car tank.

In testimony whereof, I have hereunto set my hand this 14th day of March, 1916.

WILLIAM J. TANGERMAN.
